UNITED STATES PATENT OFFICE.

ROBERT NEUSS, OF AACHEN, GERMANY.

DESIGN FOR A PIN OR NEEDLE CARD.

SPECIFICATION forming part of Design No. 28,726, dated May 31, 1898.

Application filed February 12, 1898. Serial No. 670,149. Term of patent 7 years.

To all whom it may concern:

Be it known that I, ROBERT NEUSS, of Aachen, in the Kingdom of Prussia, Germany, have invented a new and original Design for a Pin or Needle Card, of which the following is a complete specification, reference being had to the accompanying drawing, forming part thereof.

In the drawing I have illustrated a pin and needle card of novel configuration.

The card comprises a series of inwardly tapering members 1, 2, 3, and 4, the inner edges 5, 6, 7, and 8 of each of which constitute one side of a polygonal base or center

9. Each of the members 1, 2, 3, and 4 is 15 provided with a series of ribs or corrugations 10, extending approximately parallel with the lateral edges 11 and 12 of each member.

What I claim is—

The design for a pin or needle card as herein shown and described.

In testimony of all of which I have hereunto subscribed my name.

ROBERT NEUSS.
